UNITED STATES PATENT OFFICE.

CHARLES F. McBEE, OF ATHENS, OHIO.

PRESSURE-BAR FOR BOOKBINDING-MACHINES.

1,199,286.

Specification of Letters Patent. Patented Sept. 26, 1916.

Application filed April 27, 1914. Serial No. 834,588.

To all whom it may concern:

Be it known that I, CHARLES F. McBEE, a citizen of the United States, residing in Athens, county of Athens, and State of Ohio, have invented a new and useful Improvement in Pressure-Bars for Bookbinding-Machines, of which the following is a specification.

This invention relates to binding machines of the class adapted to receive loose sheets and covers, to even the same into book form and drill the perforations necessary for binding, and it has for its object to provide a pressure bar for the covers and sheets, which will also operate as a guide for the drill, a part of the said pressure bar being adapted to fold back so as to remove it from the way of the operator when he is securing the twine through the perforations.

Further objects reside in the improved means for operating the pressure bar and in the provision of means for securing the bar at any desired position.

My invention consists of certain details of construction hereinafter set forth, pointed out in my claim and illustrated in the accompanying drawings, in which—

Figure I shows a perspective view of a part of a binding machine fitted out with my improved pressure bar, the extension base being shown in a lowered position and the forward part of the pressure bar being doubled back so as to leave the volume in condition for the operator to bind; Fig. II shows a similar view the forward parts of the base and pressure bar being shown in the position necessary for drilling; and Figs. III and IV show detail views of the means I employ for securing the pressure bar at any desired position.

Referring to the accompanying drawings the reference numerals 10 and 11 are used to indicate the forward standards of a binding machine, the numeral 12 the base thereof and the numeral 13 the extension base adapted to be lowered, as shown. The numeral 14 indicates the evener board and the numerals 15 and 16 the side eveners.

Binding machines showing the above construction are now in use and are merely shown and referred to herein to form the basis of my invention.

My invention consists of an improved pressure bar and its peculiar mounting and operation. Each of the standards 10 and 11 is composed of upright parallel members

joined at their upper ends by plates 30, as shown, and the ends of the pressure bar extend through the openings thus formed. A rack 17 is secured to the outer surface of each of the standards and a gear wheel 18 is mounted on each end of the pressure bar and adapted for operation in its respective rack. The two gear wheels are similar in every respect and are mounted rigidly on a shaft 19 passing longitudinally through the pressure bar. Obviously the two racks are similar and a hand lever 20 is secured on one end of the shaft 19. It is apparent that the rotation of the lever 20 will cause the pressure bar to be elevated or lowered according to the direction of rotation of the lever. A metal strap 21 joins the two parallel members of one of the standards and secured in said strap is a set screw 22 designed to engage an upwardly extending guide member 23 of the pressure bar for clamping said guide member against the adjacent plate 30, said bar operating upward and downward on the said standard. It is obvious that the setting of the said screw will secure the pressure bar in any desired position.

The pressure bar is composed of a main body portion 24 and a forwardly hinged guide member 25 and in the said hinged portion is a longitudinal slot 26 designed as a guide through which a perforating bit (not shown) operates. This said hinged portion has a downward limit of movement which brings it in horizontal alinement with the body portion 24 and it is then held in place, during the drilling operation, by movable securing lugs 27, mounted in the manner shown. When it is desired to remove the hinged portion out of the way for binding purposes, the lugs 27 are moved inwardly against the body portion 24, and the hinged portion elevated and doubled back on the body portion, as shown in Fig. I. When this is done and the extension base 13 is dropped, as shown in Fig. I, the operator may then bind the perforated volume.

Having thus described my invention what I claim and desire to secure by Letters Patent of the United States is:

In a book binding machine, a base, spaced standards supporting the same and each comprising a pair of spaced vertical members constituting guiding elements connected at their upper ends by a plate, a pressure bar between the standards movable to-

ward and from the base and having its ends guided between the members of each standard, a rack secured on the outer face of each standard adjacent the space between the vertical members, a shaft passing through the pressure bar, a gear on each end of the shaft meshing with the respective rack, whereby on rotation of the gears the pressure bar will be moved relative to the base, an upwardly extending guide member secured to each end of the pressure bar and operating between the spaced members of the respective stand-

ards, a strap joining the component vertical members of each standard above the rack, and a screw threaded on each strap to engage and clamp the adjacent upwardly extending guide members in a predetermined position against the plate of the respective standard. 15
